United States Patent Office

Des. 178,689
Patented Sept. 4, 1956

178,689

COMBINATION PHOTOGRAPHIC MACHINE, FILM PRINTER AND VIEWER

Frank E. Oiler, Cleveland, Ohio, assignor to
Oscar Smith, Cleveland, Ohio

Application October 20, 1954, Serial No. 32,732

Term of patent 14 years

(Cl. D61—1)

The figure is a side elevational view of a combination photographic machine, film printer and viewer embodying my new design. The sides not shown are like the sides shown and the rear walls not shown are plain.

I claim:

The ornamental design for a combination photographic machine, film printer and viewer, as shown and described.
